OBADIAH MARLAND, OF BOSTON, MASSACHUSETTS.

Letters Patent No. 77,432, dated April 28, 1868.

IMPROVEMENT IN THE CONSTRUCTION OF SAFES.

The Schedule referred to in these Letters Patent and making part of the same.

TO ALL WHOM IT MAY CONCERN:

Be it known that I, OBADIAH MARLAND, of Boston, in the county of Suffolk, and State of Massachusetts, have invented an Improvement in Burglar-Proof Safes and Vaults; and I do hereby declare that the following, taken in connection with the drawings which accompany and form part of this specification, is a description of my invention sufficient to enable those skilled in the art to practise it.

The invention relates to the construction of portable safes, bank-vaults, &c., with particular reference to rendering the walls of the same more effectually burglar-proof.

The invention consists, primarily, in forming one or more of the walls of alternate plates or sheets of iron and steel, welded together throughout their adjacent surfaces, the plates or sheets being shaped and fitted together while the steel, which is welded to the iron, is in a soft or workable condition, the plates being hardened before the said parts are bolted or fastened permanently together to form the finished safe.

Also, in a peculiar arrangement of the lapping edges of the adjacent walls, and of the door.

Also, in the construction of the iron and steel bolts by which the walls are confined together.

The drawing represents a vertical section of a safe or parts of a safe embodying my invention, only the parts adjacent to the corners being shown, as the more central parts are but continuations of the plate as represented at the breaks.

The safe is not shown as lined with fire-proof packing, as my invention has nothing to do with such packing. *a b* denote the front and rear walls of the safe; *c* and *d*, the top and bottom walls or plates; *e*, one of the end walls, which, with its opposite, corresponds in general construction to the construction of the wall *b*.

Each wall is composed of a series of alternate flat plates or sections of iron and steel, (the iron being denoted by the letter *f*, and the steel by the letter *g*,) these plates being first welded together by rolling, and then fitted, and subsequently hardened, each section extending over the whole surface of the wall, of which it forms an integral portion, or so as to meet at each of its edges a corresponding section of the adjacent wall.

In bringing the plates together at the corner, to form the joints, I make a zigzag or "stepped" formation, and I then, at each two abutting steel sections, cut a portion of one section of steel away, so that the adjacent section shall project over and rest against a corresponding steel plate, as seen at *h*, so as to prevent any insertion of a chisel or other tool at the joint, to pry open the bars, the tool, in being driven between the adjacent ends, encountering the hardened steel as soon as it gets to the end of the joint. At the joints of the door *j*, the safe is similarly protected, the door being "stepped" at its edges, and the bottom of each joint being flanked or covered by a steel surface.

To secure the walls together, the inner braces or angle-bars *i* have screw-bolts *k*, made up of iron and steel in sections, a short rod or fagot being first made of iron and steel tubes, which fagot is drawn down, and has a screw cut upon its shank, (the outer surface of the bolt being of iron,) and a head swaged at its end, as seen in the drawing.

The outer-corner caps *l* are secured by bolts *m*, made and inserted as follows: Each bolt is formed of iron, and may have upon the outer surface of its shank a series of teeth, *n*. Around the hole made in the plates for reception of this bolt is a series of recesses. The shank is made hollow, or with a deep bore, *o*. At the bottom of the bolt-hole, or into the bore in the bolt, a steel pin, *p*, is introduced, this pin being of diameter larger than the normal diameter of the hole made to receive it. The bolt being riveted into the plates, is driven against this pin, the sides of which are thereby expanded or driven into the recesses in the plates, the bolt, after being thus introduced, being proof against any effort which may be made to withdraw it.

Safes called "burglar-proof," as heretofore made, of alternate plates of iron and bars of steel without being welded together, have been easily penetrated by boring through the outer plate of iron, and breaking the first plate of steel at a point opposite the hole so bored, then picking out and removing the broken pieces of said steel plate, and then boring through the next succeeding iron plate, and so continuing on through the whole series of iron and steel plates or bars, until the inside of the safe was reached.

But by constructing a safe in the manner herein described, all parts of its walls, top and bottom, and door, are rendered proof against all attempts to penetrate or force an entrance to its interior, for if the outer plate of iron is bored through, and the first plate of steel is broken, it is impossible to pick out and remove the broken pieces of steel, for the reason that they are all held firmly by the welding of the next plate of iron. Neither can any attempts at prying open the safe, or at removing the cap-pieces, or boring through the bolts, effect any success, for at every point the tool of the burglar is met by hardened steel, which he can neither break away nor penetrate.

After making all parts of my safe, and nicely fitting them to each other, I then take each part, and submit it to a degree of heat sufficient to harden, by sudden cooling, all the steel employed in the construction, by which operations I am enabled to make a safe composed of alternate plates of iron and hardened steel welded together.

In constructing the safe with a packing, I use on either or both sides of the packing, but preferably on both sides thereof, the same arrangement of series or layers of iron and steel plates welded together, as will be readily understood.

It is well known that plates of steel and iron, when welded together, will resist a much greater pressure than when the said plates are simply laid one over the other, or than when they are riveted together. Therefore the welded plates of steel and iron in my safe have a great advantage in strength over all other constructions of burglar-proof safes.

I am aware that safes have been made, and, as I believe, for many years past, in which the plates forming one of the walls or sides of the safe are each made up of bars, so that in each boundary there are several joints, viz, one at each abuttal of adjoining bars, while in my safe I have no joints, except at the corners, and those connected necessarily with the door.

I claim a safe or bank-vault, the boundaries of which are made up of or are protected by entire compound plates, each of which is constituted of plate-layers of iron and steel welded together, the steel layer or layers of each laminated plate being hardened, substantially as shown and described.

I also claim the formation of the joints at the corners of the safe, and at the edges of the door, so that the bottom of each section of joint is covered by steel, substantially as shown and described.

I also claim the bolts *k*, made of alternate tubes of iron and steel, drawn and welded together, substantially as set forth.

Also, inserting the bolts *m* into holes prepared, substantially as described, for their reception, and then changing the form of the bolts by pressure or percussion, so that thereby, and with the conjoined action of a spireader, *p*, the bolts *m* will hold in their sockets, substantially as described.

OBADIAH MARLAND.
